DUPLICATING MACHINE

Filed Jan. 16, 1931

UNITED STATES PATENT OFFICE

LOUIS JENSEN, OF CHICAGO, ILLINOIS, ASSIGNOR TO UNITED AUTOGRAPHIC REGISTER CO., OF CHICAGO, ILLINOIS, A CORPORATION OF ILLINOIS

DUPLICATING MACHINE

Application filed January 16, 1931. Serial No. 509,239.

This invention relates particularly to duplicating machines of the general type known as autographic registers.

The primary object of the invention is to provide a machine which will enable a plurality of strips which have been folded into a zigzag packet to be drawn from the packet, have the slips filled in, advance the strips, and divert one or more of the strips to be dispensed by the machine while the remainder are refolded and preserved in the machine, special provision being made for assuring the proper folding in the storage compartment.

15 The invention is illustrated in a preferred embodiment in the accompanying drawing, in which—

Figure 1 is a vertical longitudinal sectional view of a duplicating machine embodying the invention; Fig. 2, a broken vertical transverse section taken as indicated at line 2 of Fig. 1, showing the feed mechanism; and Fig. 3, a perspective view showing the lower side of the cover for the storage compartment of the machine.

In the construction illustrated, A represents a casing provided with a platen A', a compartment A² for containing a supply packet, a compartment A³ for receiving the record strip, and a cover A⁴ which serves as a top for the compartment A³; B and C designate upper and lower feed roll shafts, respectively, which are journaled on the casing above the rear portion of the compartment A³; and B' and C', gears connecting the shafts B and C so that the shafts will rotate together at a predetermined ratio.

Any desired number of strips may be fed through the machine. In the illustration given, two strips are shown, namely, a lower strip G which constitutes the record strip, and an upper strip G' which is dispensed by the machine. The supply packet from which the strips are drawn is designated G², and the record packet which is formed in the compartment A³ is designated G³.

Any suitable feed mechanism may be employed in connection with the present invention and no invention is claimed for the one shown, which is well known in the art. The

strips are advanced by the feed roll 1 pressing the strips against the feed rolls 2—2. Register perforations are provided at regular intervals in the paper strips and when they reach the feed rolls the advance stops, as no traction is exerted on the strips and register pins 4 are provided to engage the perforations.

To advance the next set of forms a latch 5 is raised which permits the clutch 6 to engage an initial feed wheel 6^a and by turning the crank C² the strip is advanced sufficiently by the wheel 6^a to enable the normal feed rolls 2 to engage the paper and continue the feeding operation, as will be readily understood by those familiar with the register art. A lever 7 may be provided to raise the feed roll 1 when it is desired to introduce new strips.

The cover A⁴ is shown as comprising a main section 8, an auxiliary section 9 which is hinged to said main section, and a concavo-convex deflector plate 10 which is hinged from the auxiliary section 9. The marginal side portions of the section 8 may be bent downwardly and provided with perforation 8^a to receive a rod 11 which serves as a pivot for the cover. The rearward edge of the section 9 serves as a separator for the strips G and G'. The hinged connection between the sections permits the edge to be positioned very close to the rolls and still allow the cover to be swung open without removing the rod 11. If desired a locking device 12 may be provided to prevent anyone, not having a key, from tampering with the record strip. Uprights 14 are shown in each of the compartments to hold the packets in proper position.

In order to assure that the record strip or strips will be properly refolded in the storage compartment it is important that the plate 10 be properly shaped and positioned. Heretofore such guide plates have been rigidly connected to the cover and difficulty was experienced in getting the strip to fold properly when the storage compartment contained a rather thick packet. It has been proposed to place long swinging fingers of various curvatures near the center of the compartment or even farther back from the feed rolls.

Such devices have been found ineffectual in preventing the strips from buckling in the wrong direction when the compartment was rather full. In the present invention it has been discovered that by hinging a rather light concavo-convex guide plate to the cover member, with the concave side towards the feed rolls so as to be close to the feed rolls, that the guide plate is in almost constant contact with the strip coming into the compartment and that although the strip will exert sufficient force to swing the guide back when folding in the front of the compartment, the guide will keep the strip buckled properly so that it will fold satisfactorily at all times.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In an autographic register: a casing equipped with a platen, the front portion of said casing serving as a storage-chamber; means for feeding paper strips from a zig-

zag folded packet across said platen into said chamber; and a withdrawable cover for said chamber having a main section pivotally mounted on the forward portion of said casing, an auxiliary section hingedly mounted on said main section, and a concavo-convex strip-following guide plate hingedly mounted on said auxiliary section with its concave face towards and near said feed means serving to direct the folding of a strip in the storage chamber.

2. In a register: a casing equipped with a platen, the front portion of said casing serving as a storage compartment; devices, including a lower feed-roll for feeding a plurality of strips across said platen from a zig-zag folded packet; means for separating at least one of said strips and discharging same into said compartment; a strip-following guide-plate presenting a concave surface towards said feed-roll pivotally suspended from the upper portion of said storage-compartment and adapted to contact with the depositing strip; and a transverse fixed guide interposed between said guide-plate and feed-roll.

LOUIS JENSEN.
